EDWARD BURNHAM, OF FRAMINGHAM, MASSACHUSETTS.

Letters Patent No. 89,553, dated May 4, 1869.

IMPROVED ROPE-GUIDE FOR WINDOW-WEIGHTS.

The Schedule referred to in these Letters Patent and making part of the same.

To all persons to whom these presents may come:

Be it known that I, EDWARD BURNHAM, of Framingham, in the county of Middlesex, and State of Massachusetts, have invented a new and useful or improved Anti-Friction Window-Weight Rope-Guide; and I do hereby declare the same to be fully described in the following specification, and represented in the accompanying drawings, of which—

Figure 1 is a top view;

Figures 2 and 3 are end views;

Figure 4, a side elevation;

Figure 5, a longitudinal section; and

Figure 6, a transverse section of it.

It is to be made of glass; and

It consists of a cylinder, A, having a circumscribing flange, a, projecting from one end of it, and a small ear or projection, b, extended from its curved surface, near its other end.

It also has a rope-channel, c, formed lengthwise through its side, and into each end of it, such channel being curved both longitudinally and laterally in manner as represented.

This rope-guide, when used, is to be inserted in a

cylindrical hole, made in the window-frame, the upper part of such hole being grooved lengthwise to receive the rope, and also to allow of the insertion of the guide in the hole, the projection b going through the groove.

Afterward, by turning the cylinder so as to bring the groove upward, the projection b, by resting against the front of the weight-chamber, will prevent the guide from being drawn out of place.

The flange will also aid in preserving the guide in its place in the hole.

The advantage of this rope-guide over many other glass guides in use is that a round hole, bored with a bit and grooved as described, is all that is necessary for its reception.

I claim the improved window-weight rope-guide, made as described, viz, as a cylinder having a flange, a, at one end, a projection, b, at the other, and a rope-channel, c, arranged as specified.

EDWARD BURNHAM.
